DRAWING MACHINE

Wallace E. Kerr, Youngstown, Ohio

Application August 24, 1938, Serial No. 226,477

32 Claims. (Cl. 205—3)

1

This invention relates to a drawing machine of the kind in which lengths of metal sections are drawn through restricting or forming dies for the purpose of reducing or forming the cross-sectional area or shape of the pieces. In machines for this purpose it is common practice to provide a die block, a frame or track extending away from the leaving side of the die or dies, a carriage movable along the track and having means to grip reduced end portions of the pieces extending through the dies, means for removing the pieces from the machine, as shown in my prior U. S. Patent #1,940,354, for example, and a moving chain to move the carriage away from the die block.

To effect substantial economy in the production of drawn shapes it is, of course, essential that the driving machine be automatic in its operation—requiring but one operator for its operation, and capable of wide flexibility in use while requiring a minimum of time to change over from one kind of operation to another. By the latter is meant the rearrangement of the machine for the production of shapes having different cross-sectional shapes or sizes and as this normally involves an interchange in the members used to grip the reduced end of the stock extending through the die, the construction of the grip bit assembly on the carriage is such that the grip bits may be readily rearranged and interchanged with a minimum of delay. Inasmuch as the machine may be of sufficient capacity to draw but a single length of bar or tube of one size and a plurality of lengths of smaller size the construction enables either one or a plurality of such lengths to be simultaneously drawn, depending on the size and material of the stock being drawn and the manner in which the machine is set up. It is one object of my invention to provide a grip bit and grip bit operating assembly for use in a machine of the kind described in which the bits are of simple and inexpensive design and capable of being readily interchanged when preparing the machine for operation on different products.

Another object of the invention is to provide an improved construction for the grip bit operating assembly in which substantially the entire mechanism thereof is housed within the frame of the carriage thereby minimizing the danger of injury to such mechanism by impact between the frame and/or mechanism and other objects. This feature of design is accomplished without sacrificing any of the desirable attributes concerning the ruggedness and ease of interchange-

2

ment of the bits as mentioned above and results in a machine requiring less maintenance and having a higher long term efficiency than any such machines heretofore devised.

A further object of the invention is the provision of improved apparatus for returning the grip bit carriage to the die block upon the completion of a drawing operation and this includes means to quickly return the carriage to a position adjacent the block, means to retard the speed of the carriage as it approaches the block, and means to hold the carriage in contact with the block until the grip bits have effectively engaged the reduced ends of the bars or tubes extending through the dies of the block. These features are of importance since a quick return of the carriage decreases the time consumed in unproductive phases of the operation of the machine, the reduction in speed prevents injury to the carriage and die block assemblies due to shock, and the elimination of rebound of the carriage after contacting the die block enables the grip bits to engage the stock ends at a position very close to the dies thereby reducing the length of the reduced or pointed end required to be placed on each length of stock which reduced ends must subsequently be severed for scrap. By reducing the percentage of scrap evolved in the drawing process substantial economies are effected.

Yet another object of the invention is the provision of an improved means to retain the chain engaging hook in retracted position when the carriage is returned to the die block and an improved mechanism for operating the grip bits upon the fall of the hook as the carriage reaches the die block whereby no undue stresses are imposed on any of the parts, wearing surfaces may be of substantial area, and the mechanism, as a whole, may be subjected to continuous and heavy service with a minimum of repair and adjustment.

A still further object of the invention is the provision of a cable mechanism for returning the grip bit carriage to the die block in which the shaft of the cable driving sheave is relieved from stresses imposed by the static tension in the cable and in which the cable maintains a fixed position axially of the driving sheave at all times whereby the elements may be of simple and economical design and delays incident to any carriage return mechanism failure may be substantially obviated.

These and other objects and advantages of the invention will become apparent from a consid-

eration of the following detailed specification and accompanying drawings of a preferred embodiment of the invention. Throughout the several views of the drawings, similar reference numerals designate similar parts; and

Figure 1 is a partial side view of a drawing machine embodying the principles of my invention;

Figure 2 is a plan view of the structure of Figure 1;

Figure 3 is a plan view, partly in section, of the grip bit carriage assembly of the machine of Figure 1;

Figure 4 is a plan view, partly in section, of a portion of a modified form of grip bit assembly, illustrating the manner in which the corresponding assembly of Figures 2 and 3 is changed in order that the machine may simultaneously draw two bars or tubes instead of three as in Figures 2 and 3;

Figure 5 is a plan view, partly in section, of a portion of a modified form of grip bit assembly, illustrating the manner in which the corresponding assembly of Figures 2 and 3 is changed to draw but a single tube or bar at each traverse of the carriage;

Figure 6 is a plan view, partly in section, of another modified form of grip bit assembly;

Figure 7 is an end view of the grip bit carriage of Figures 2 and 3;

Figure 8 is a sectional view of the grip bit carriage taken along the line 8—8 of Figure 3;

Figure 9 is a longitudinal section of the grip bit carriage taken along the line 9—9 of Figure 3;

Figure 10 is a longitudinal section of the grip bit carriage taken along the line 10—10 of Figure 3;

Figure 11 is a sectional view taken along the line 11—11 of Figure 3;

Figure 12 is a sectional view taken along the line 12—12 of Figure 2; and

Figure 13 is a wiring diagram, illustrating the energizing and control circuits for the carriage return mechanism.

Referring now more particularly to Figures 1 and 2 of the drawings, the machine to which the various features of my invention may be applied consists of a bench 10 having a pair of spaced parallel tracks 11 on which travel the wheels 23 supporting the grip bit carriage frame 20. Connected with one end of the bench 10 is the die supporting frame generally indicated at 12 which is adapted to slidably receive the die block 13, the former being provided with grooves 15 into which the ribs 14 of the latter move to prevent relative movement between the parts during the normal operation of the machine. Block 13 supports the restricting or forming dies 16 through which rods or tubes 17 are to be drawn and to initiate operation of the draw, the rods, tubes or other lengths 17 are first provided with an end portion 18 reduced in diameter to pass through the openings in dies 16 for engagement by the gripping means carried by the frame 20. The latter is provided with a depending side member 24 to which the ends of the carriage moving cable 25 is attached, one end having an adjustable connection 26 with the member whereby the tautness of the cable may be varied. In accordance with usual practice an endless and continuously moving chain 22, only a portion of which is shown, is utilized to transmit the power required to move the carriage 20 away from the die block 13 and draw the shapes being worked

through the dies 16, the chain 22 having a reach extending along the bench 10 between the tracks 11 and continuously moving away from the dies 16. A hook 21 connects the grip bit carriage with the chain 22 and in the normal operation of the machine the hook 21 automatically drops and engages the chain 22 as the carriage 20 reaches the die block 13 and disengages from the chain upon completion of the drawing operation thus enabling the cable 25 to return the carriage back to the dies.

The grip carriage assembly of my invention, including the preferably unitary frame member 20 having a longitudinal recess for the reception of the hook 21, as shown in detail in Figures 3 to 11, inclusive. Hook 21 is pivotally mounted on the transversely extending pin 28 and is provided on its upper surface adjacent its outer end with the attached member 29 having laterally extending portions for engagement with the shoulders 30 on the side arms of the pivotally mounted fork 29'. The lower ends of the arms of fork 29' are pivoted to frame 20 by the spaced axially aligned pins 31 and with the member 29' in retracted position, as shown in Figure 9, the shoulders 30 and laterally extending portions of member 29 cooperate to maintain the hook in raised position. An outward or counterclockwise movement of member 29' moves shoulders 30 away from member 29 allowing hook 21 to rotate about pin 28 and the hook to impinge on chain 22. Fork 29' is operated by rod 32 which pivotally connects with a pin 33 extending laterally from the upper portion of the fork and which is biased by coil spring 34 toward the die block end of the carriage to normally hold the fork in retracted position. Rod 32 is, in turn, actuated by the rod 35 the die block end of which is adapted to engage a projection 36 on block 13 as the carriage approaches the die block.

Carriage frame 20 is provided at one end with a transverse recessed slot 36' into which is adapted to slide the grip bit block 37 having inner flanges 38 fitting within the recesses to prevent longitudinal separation of the frame and block 37. Referring to Figure 3 which illustrates the grip assembly as set up to simultaneously draw three bars or tubes, the block 37 is provided with three pairs of converging guide channels 39 each adapted to slidably receive a grip bit 40 having an angular disposed serrated portion 41 to grip the reduced ends 18 of the bars or tubes being drawn. The channels 39 converge toward the outer face of block 37 whereby movement of the bits of a pair toward said face cause the serrated portions thereof to move toward each other and securely clamp the intervening end 18 of the bar or tube. The design of the parts is such that the outer side surfaces of the channels of a pair, which surfaces receive the entire thrust imposed by the clamping of the rod or tube portion 18, are uninterrupted through the length of the channels thereby increasing the wearing surface and adding to the life of the assembly. The grip bits 40 which may be constructed of stock which is square or rectangular in cross-section are of simple design for economy of construction and inasmuch as they are of uniform cross-section they may be readily removed individually through their respective channel openings to the outer face of the block 37. For a purpose to be later described, each of the grip bits adjacent its end opposite the serrated portion is provided with a vertically disposed bore 42.

Grip bits 40 are slidably moved longitudinally

in their respective channels by the plungers 44 which abut the inner ends of the bits to move the same outwardly and by the inverted U-shaped connecting rods 45 the adjacent ends of which are received within the bores 42 to move the bits inwardly. The outer faces of the plungers 44 and the adjacent faces of the grip bits 40 are plane and parallel thereby providing substantial contacting areas for the transmission of the forces required to move the bits into tight engagement with the stock being worked on. Plungers 44, which in the embodiment of Figure 3 are six in number, are mounted in parallel relation for sliding movement longitudinally of the bench 10 in suitable bores provided in the frame 20. Adjacent the end of each plunger opposite its grip bit engaging surface is a collar 47 which is suitably secured to the plunger 44 and which is provided with a vertical bore 48 aligning with a bore 49 in the plunger to receive the other end of the inverted U-shaped connecting rod 45. Collar 47 being secured to the plunger moves the rod 45 in accordance with the movement of the plunger. The collars 47 are each provided with a depending lug 50 slidably received within slots 51 in the frame 20 to maintain the collars and consequently the rods 45 in proper vertical position.

Plungers 44 are urged to simultaneous longitudinal movement upon pivotal movement of the hook 21 by means of the connecting linkage now to be described. Extending transversely of the upper portion of the frame 20 is the pin 53 on which is rotatably mounted the sleeve 54 having attached thereto the downwardly extending widely spaced arms 61 and the centrally disposed spaced arms 55. Spanning the outer free ends of arms 55 is the pin 56 which is rotatably mounted in aligned apertures in the arms and which is provided with a diametrically disposed threaded bore for the reception of a hollow screw 57. The latter is rotatably mounted on a threaded rod 59' which is rigidly connected at its lower end with a fork 59 pivotally attached at 60 to the hook 21 at a point adjacent the pivot 23. The upper end of screw 57 is provided with an attached collar 57' and a second collar 58 is screw threaded onto the outer end of threaded rod 59'. By loosening collar 58, screw 57 through collar 57' may readily be rotated thus providing an adjustment of the interval between pin 56 and pivot 60. A transverse member 62 having apertures 63 for the accommodation of plungers 44 is connected with the lower free ends of the arms 61 by the U-shaped links 64 which are rigidly attached at their one end to the transverse member 62 and which are pivotally connected, by means of pins 65, with the arms 61 at their other ends. As shown in Figures 9 and 10, the frame 20 is provided with a cavity 66 of sufficient size to accommodate member 62 and to allow said member a limited movement longitudinal of the bench 10 with respect to the frame 20. A coil spring 67 is interposed between each collar 47 and the transverse member 62 and a second set of coil springs 68 are interposed between the member 62 and the enlarged ends 69 of the plungers 44. It can therefore be seen that longitudinal movement of the member 62 along the axes of the plungers 44 causes the plungers and consequently the grip bits 40 to move along their longitudinal axes and the bits to move to their operative or inoperative positions. As shown in Figure 3, the links 64 are positioned intermediate certain of the plungers 44 so as not to interfere with the proper operation of the latter.

Returning to Figures 1 and 2 of the drawings, the apparatus provided to return the grip bit carriage to the dies and to move the carriage independently of the chain 22 when no load is imposed includes the cable 25, as mentioned above, which is driven by a novel driving arrangement now to be described. I provide a driving motor 71 having an attached speed reducing unit 72 the driven shaft 73 of which has keyed thereto inner and outer driving disks 74 and 75, respectively. See Fig. 12. Disks 74 and 75 are urged toward each other by a spring 76 interposed between a nut 77 on the outer end of extension 78 of shaft 73 and the outer surface of disk 75. Interposed between the disks 74 and 75 is the double groove sheave 80 driven solely by the inner faces of the disks 74 and 75. Suitable friction material 81 is interposed between the faces of sheave 80 and the inner faces of the disks mentioned. Spring 76 is so adjusted that sufficient power to move the carriage may be transmitted through the friction clutch thus provided but if excessive resistance is encountered, the clutch will slip. A single groove sheave 83 is supported on an inclined axis on one side of the driving sheave 80 and a second single groove sheave 84 is mounted on an inclined axis on the other side of sheave 80. A pulley 85 is mounted adjacent the end of the bench 10 opposite the die block and a second pulley 86 is mounted adjacent the die block. Beginning with that end of cable 25 fixed in relation to member 24 the cable may be traced—over pulley 86, sheave 80, sheave 84, sheave 83, sheave 80, pulley 85 and back through adjustable connection 26 to member 24. The purpose of the inclined axes for sheaves 83 and 84 is to provide aligning guide surfaces between the cable leaving increment of one sheave and the cable entering increment of the subsequent sheave. The arrangement provides a length of contact between the cable 25 and the driving sheave 80 equal to or slightly greater than the entire circumference of the sheave 80 thus providing a drive of sufficient capacity to quickly move the carriage along the bench. Also the arrangement enables the drive to be accomplished by the use of but two parallel grooves in the driving sheave thereby dispensing with any movement of the point of application of the force caused by tensioning of the cable, axially along the shaft supporting the sheave. Consequently bending moments of less value are applied to the shaft and the shaft and its support may be made lighter in construction and will be less likely to be damaged in use.

The control circuit for the grip bit carriage return motor 71 is illustrated schematically in Figure 13. Motor 71 is of the reversing type and is provided with a magnetic brake 172 of the usual kind in which the braking force is applied by a spring and released by a solenoid, as 92, which is energized simultaneously with energization of the motor. A normally closed limit switch 88 having an operating arm 89 adapted to be engaged by depending member 24 of the carriage is positioned on the bench 10 a number of feet from the die block 13 and a second double throw limit switch 90 having an operating arm 91 also adapted to be engaged by depending member 24 is positioned adjacent the die block in such manner that when the outer face of block 37 is within a short distance of the die block or is in contact therewith, the switch will be in right closed position as viewed in Figure 13. A third limit switch 94 having an operating arm 94a

operated by a member 83a (see Figure 12) through friction clutch 83' driven by sheave 83 is adapted to be operated upon reversal of direction of movement of the cable 25. The operation of this assembly is such that upon a change in the direction of movement of the cable and consequently of sheave 83, the member 83a rotates until the switch arm 94a is thrown to its other limiting position whereupon member 83a stops—further rotation of 83' being permitted by the frictional connection between 83' and 83a.

Figure 13 illustrates the condition of the controls immediately after the return switch S2 has been manually actuated and the carriage is returning to the dies. Actuation of S2 established the relay circuit—line, conductor 106, 106a, 106b, solenoid S05, conductor 105, 105a, switch S2, conductor 111a, 111, 112, normally closed switch S1, and back to line. Energization of solenoid S05 closed the switch S5 and S5a thereby energizing the return windings of the motor thru line, conductor 106, 106c, switch S5a, conductor 96a, 96, motor 71, conductor 97, 98, 130a, switch S5, conductor 130, 119, 116, 112, switch S1, and back to line. Simultaneously a holding circuit for solenoid S05 consisting of line, conductor 106, 106a, 106b, S05, 105, 103, 103a, S3, 102, 101, 90, 100, 88, 99, 130a, S5, 130, 119, 116, 112, S1, and back to line was established and consequently the return energization of motor 71 continues when switch S2 is released. Return of the carriage continues at uniform speed, which by reason of the arrangement to be hereinafter described may be considerably higher than that previously employed, until limit switch 88 is actuated by engagement of its operator 89 by member 24 depending from the carriage. Opening of switch 88 breaks the holding circuit above defined and deenergizes solenoid S05 allowing switch S5 and S5a to open thereby opening the motor energizing circuit. Opening of switch S5 also breaks the relay circuit—line, conductor 131, 126, solenoid S08, conductor 132, 98, 130a, S5, 130, 119, 116, 112, S1, and back to line; deenergizing solenoid S08 and opening switch S8 which switch maintains an energizing circuit—line, switch S1, conductor 112, 116, 124, brake releasing solenoid 92, conductor 122, 123, S8, 125, 133, 131, and line; for operation of solenoid 92 and release of brake 172. Consequently, as the carriage reaches switch 88, and motor 71 is deenergized and the brake 172 is applied which in addition to applying its effect to the motor 71 per se also acts on the cable 25 thereby exerting a braking action on further movement of the carriage.

Inasmuch as the carriage assembly is of considerable weight substantial inertia is inherent in the same when it is moving and it will continue to drift some distance after motor 71 is deenergized and brake 172 is applied. Brake 172, and if necessary, friction drive 74, 75, 80 are so adjusted that the carriage will drift to substantial engagement with the die block or at least until the limit switch 99 is engaged. This results in opening above defined holding circuit and energizing solenoid S05 through line, 103, 106a, 106b, S05, 105, 103, 103a, S3, 102, 102a, 90, 108a, 108, 104, 111, 112, S1, and back to line and closing switch S5 and S5a establishing motor energizing circuit—line, 106, 106c, S5a, 96a, 96, motor 71, 97, 98, 130a, S5, 130, 119, 116, 112, S1, and back to line—which energization of motor 71 will move the carriage into positive engagement with the die block and maintain the engagement until the main draw chain 22, through hook 21, begins to

move the carriage away from die block. Referring now to Figures 3, 8, 9, and 10 of the drawings, as the carriage 20 approaches the die, the stock 17 to be drawn, will have their reduced ends 18 in position extending through the dies and these ends will be received between the opened serrated jaws 41 of the grip bits 40. As the approach is completed the engagement of rod 35 with projection 36 moves the fork 29 counterclockwise releasing latch 29—30 and allowing hook 21 to fall onto chain 22. This causes sleeve 54 to be rotated by linkage 55—59 consequently rotating arms 61 and moving links 64 toward the grip bits. As the transverse member 62 is connected with the links 64 it will also be moved toward the grip bit end of the carriage and through springs 68 acting on plungers 44 it will urge the plungers toward the same end of the carriage. As clearly shown in Figure 3 such movement of the plungers will move the grip bits 40 along their channels and the bits of each pair will move toward each other and securely clamp the stock ends 18 to the carriage. Now as the bight of the hook 21 drops into a dwell of the chain 22, if it did not do so initially, the carriage and consequently the stock will be drawn along the bench. During that interval between the time the carriage reaches the die block and the time the chain 22 through hook 21 begins to move the carriage away from the block the pressure contact between the carriage and the block is maintained through cable 25 by motor 71, the friction clutch 74, 75, 80, 81 (Figure 12) slipping.

To prevent energization of motor 71 opposing forward movement of the carriage during the drawing cycle, the switch 90 normally returns to the position shown in Figure 13 and upon such movement and consequent reversal of direction of movement of cable 25, switch 94 will close. As shown in Figure 13 the switch 90 deenergizes solenoid S05 by opening circuit through—line, 106, 106a, 106b, S05, 105, 103, 103a, S3, 102, 102a, 90, 108a, 108, 104, 111, 112, S1, and back to line as previously defined, opening switch S5 and S5a which opens the motor energizing circuit—line, 106, 106c, S5a, 96a, 96, motor 71, 97, 98, 130a, S5, 130, 119, 116, 112, and S1—previously defined and at the same time the solenoid 92 which releases brake 172 is energized by circuit—line, S1, 112, 116, 124, solenoid 92, 122, 121, 127, 94, 120, 133, 131, and back to line. Consequently the brake is released and is inoperative during the drawing traverse of the carriage.

In addition to the above described features of the return motor control circuit I provide arrangements whereby the carriage may be controllably moved either forward or backward along the bench regardless of the position of the same. The former is accomplished by depressing switch S4 which energizes solenoid S06 through line, 106, 106a, 106c, S06, 107, S4, 108b, 108, 104, 111, 112, S1, and back to line. Energization of S06 closed switch S6 and S6a providing the motor energizing circuit—line, 106, 106d, S6a, 114, 96, 71, 113, 130c, S6, 130b, 119, 116, 112, S1, and back to line. Upon release of switch S4 the circuits mentioned are opened and the motor is deenergized and the brake 172 applied thereby providing a very sensitive carriage positioning control. To release brake 172 upon such motor energization the closing of switch S6 energizes solenoid S07 through line, 131, 117, S07, 137, 130c, S6, 130b, 119, 116, 112, S1, and line which solenoid closes switch S1 providing a circuit—line, S1, 112, 116, 124, 92, 122, 121, 115, S7, 118, 133, 131, and line—

thereby energizing brake releasing solenoid 92. The carriage may be controllably moved toward the dies by depressing manual switch S3 which establishes the circuit—line, 106, 106a, 106b, S05, 105, 103, 109, S3, 110, 104, 111, 112, S1, and line—and closes switch S5 and S4a closing the motor energizing circuit defined above. Simultaneously solenoid S08 is energized thru-line, 131, 126, S08, 122, 98, 130a, S5, 130, 119, 116, 112, and S1—closing switch S8 thereby energizing brake releasing solenoid 92 through line, S1, 112, 116, 124, 92, 122, 123, S8, 125, 133, 131, and line. Upon release of S3 the circuits completed thereby are opened, the motor deenergized and the brake applied. A fourth manual switch S1 is provided to stop the carriage when moving as a result of energization of motor 71 by previous closure of S2 or by the failure of switches S3 and S4 to open upon release. Opening of S1 breaks the holding circuit described above and opens any circuit established by actuation of manual switches S3 and S4.

In operation, the lengths of stock are fastened to the carriage in the manner and by the mechanism described above and as the chain 22 takes the load it rises to the position shown in Figure 1 by reason of the elevation of pivot pin 28 and thereby lifts the hook 21 up sufficiently to position member 29 above the shoulders 30 of member 29'. Spring 34 draws member 23' into retracted position upon disengagement of rod 35 with projection 36 and in this position of the parts the draw continues until the stock 17 has passed through the dies. As the stock leaves the dies the carriage will accelerate in a forward direction causing the chain to fall away from the hook 21 which will be maintained in upper position by the member 29 resting on shoulders 30. Inasmuch as the transverse member 62 will have moved forwardly when the hook raised with the chain 22, the springs 67 between member 62 and collars 47 will be compressed and as the tension on the stock 17 ceases thereby stopping the outward pull on the grip bits 40, the collars 47 and plungers 44 will move in a direction away from the grip block 37 and by reason of the connecting rods 45 the grip bits will also be moved in the same direction to open the pairs thereof and allow the stock ends 17 to be removed therefrom. The bits remain in open position until the hook 21 again falls by engagement of rod 35 with the projection 36 or by manual manipulation of member 29', the projecting pin 33 of which provides a hand grip member.

To provide means to raise the hook 21 during forward movement of the carriage irrespective of the load and tightness of chain 22 a pair of cam members 140 are positioned on opposite sides of the chain 22 adapted to be engaged by a pair of members 141 secured to and depending from opposite side faces of the hook. If the hook is down when cams 140 are reached, the lower surfaces of depending members 141 ride up the inclined upper surfaces of members 140 thereby raising the hook sufficiently to permit attached member 29 to snap over the shoulders 30 of member 29' and retain the hook in raised position.

A dash pot 144 acting through pivoted lever 145 engageable by the carriage as it nears the die block may be employed to cushion the impact between the carriage and the die block.

As stated above, the grip bits 40 are carried in a block 37 which is slidably mounted in the carriage frame 20. Block 37 is retained in position in the frame by the pin 37' which passes down-

wardly through aligned openings in the frame and block. To remove the block it is only necessary to withdraw pin 37' and connecting rods 45 whereupon the block may be slid transversely out of the carriage frame. As apparent from Figure 3 the frame 20 is provided with openings allowing ready access to the rods 45. Block 37 may be replaced, for example, by a block 371 as shown in Figure 4 in which but two pairs of grip bits 401 are included. The set up may be used to draw stock 181 of larger size than it would be possible to draw in a triple machine. Certain of the plungers 44 and certain of the collars 47 and rods 45 would be utilized to operate the grip bits 401. Aside from the withdrawal of rods 45 which is an exceedingly simple operation no parts of the grip bit operating mechanism need be touched in the changing of individual grip bits or in the changing of the grip bit block assembly. In Figure 5 there is shown a block 372 which houses but a single pair of grips 402 for operation on very large or heavy stock. When assembled with the other parts of the carriage, a pair of plungers 44 and a pair of rods 45 are utilized for the actuation of each of the grip bits 402 thus insuring adequate force for the actuation of the heavier bits. In each of three modifications thus far described the operation is the same.

Figure 6 illustrates a modified form of carriage in which the grip bits 403 are not mounted in a removable block but are mounted in guides provided in the carriage housing 203. Transverse member 62 is dispensed with and the collars 623 on each of the two plungers 443 are connected directly with the links 64. As in the other embodiments the plungers 443 move the grip bits 403 toward each other and the rods 453 connecting the bits with collars 473 fixed on the plungers move the bits away from each other.

The adjustment 56, 57, 58 may vary the position of the transverse member 62 or the collars 623 with respect to the carriage frame and may consequently alter the position of and interval or intervals between a pair or pairs of the grip bits when the hook is in raised position in which position of the parts the grip bits move about the stock ends projecting through the dies. If the stock is small in cross-section the pairs of bits are moved closer together to insure tight gripping upon fall of the hook and if the stock is large in cross-section the grip bits are moved further apart. This is the only adjustment necessary for the proper operation of the grip bit operating mechanism and the design of the assembly permits this adjustment to be positioned in a readily accessible location. Incidentally this is the only element of the mechanism which projects beyond the general outer contour of the grip bit carriage assembly, practically all the parts thereof being located within the casing or housing in nested and protected positions.

It can thus be seen that I have provided an improved metal drawing machine which accomplishes the objects initially set out. The devised control for the movement of the grip bit carriage enables the machine to be operated at higher productive speeds and allows a reduction to be effected in the amount of the stock utilized in the provision of the requisite reduced end for each length thereby substantially reducing the scrap losses incident to the operation of the process. Assuming a constant supply of pointed stock to be made available at the dies by any of the means well known in the art the drawing machine operator need normally to perform but few operations

during each drawing cycle as the momentary depressing of the return control switch S2 upon completion of a draw will result in automatic control of the subsequent movement of the carriage in the manner described above. The grip bits which must be replaced from time to time because of normal wear are very simple in design and are consequently economical to construct. The bits may be readily replaced individually and the entire grip bit assembly may be readily removed from and inserted in the carriage thereby facilitating the setting up of the machine for operation on different products. The interchanging of the individual bits and of the bit assemblies requires little technical knowledge on the part of the operator and no special tools and the same may be accomplished without disturbing the more complicated parts of the machine. By positioning the latch 29-30 near the center of the unsupported mass of the hook 21, the latch is subjected to minimum force and will consequently render long trouble-free service. Also, less force will be required to release the latch to allow the hook to drop onto the chain 22. By providing plane contacting surfaces of substantial area between the plungers 44 and the grip bits the life of the grip bit operating mechanism will be materially lengthened.

Important features of my invention include the arrangement and design of the grip bits and the grip bit operating mechanisms. As the grip bits are individually resiliently urged to closed positions by the springs 68 acting through their respective plungers 44, inaccuracies in the shape and disposition of the pointed ends of the stock to be drawn will not effect the operation of the gripping assembly for the reason that in all instances each of the grip bits of a gripping pair will be independently moved into pressure engagement with the end portion of the stock. Springs 68 perform the additional function of cushioning the shock transmitted to member 62 by the sudden movement of the grip bits when the last of the stock leaves the die. It should be observed that the grip bit operating elements 44, 45, 47, 62, 67 and 68 are ruggedly mounted in protected positions in the body of the frame 20 and thus are capable of withstanding severe conditions of service without failing. While I have specifically described these elements as being operable upon movement of a chain engaging hook it should be obvious that other means may be employed to transmit drawing movement to the carriage and that other mechanism may be employed to actuate the said elements.

The above specifically described embodiments of my invention should be considered as illustrative only as obviously many changes may be made therein without departing from the spirit or scope of my invention, the extent of which is indicated by the subjoined claims.

What I claim is:

1. In a drawing machine, the combination of a carriage having a member movable upon engagement with an element independent of said carriage, a stock engaging grip bit movably mounted on said carriage for movement into open and closed positions, a motion transmitting element connected with and moved by said first mentioned member, means to transmit motion from said element to said grip bit in a closing direction, and removable means connecting said element and said grip bit to transmit opening movement to said grip bit, said last mentioned means

being removable without disturbing said first mentioned means.

5 2. In a drawing machine, a carriage having guide surfaces thereon, grip bits carried by said carriage and slidable along said surfaces into engagement with the stock to be drawn, controlled means on said carriage to move said grip bits into engagement with said stock, said means applying a resilient force to said grip bits, and means including quickly removable links connecting said grip bits and first mentioned means for moving said grip bits in the opposite direction.

15 3. In a drawing machine, the combination of a carriage having an operating member thereon, a stock engaging grip bit movably mounted on said carriage for movement into open and closed positions, a motion transmitting element connected with and moved by first said mentioned member, means to transmit motion from said element to said grip bit in a closing direction, and a movable means connecting said element and said grip bit to transmit opening movement to said grip bit, said last mentioned means being removable without disturbing said first mentioned means.

20 4. In a drawing machine, the combination of a carriage having a member movable upon engagement with an element independent of said carriage, a second member on said carriage normally located in an elevated position and adapted when moving downwardly to originate a moving force, a third member mounted on said carriage and adapted to move rectilinearly, means connecting said first and second members whereby actuation of the former will result in downward movement of the latter, means connecting said second and third members whereby movement of the second member will be transmitted to the third member, and a stock engaging grip bit slidably carried by said carriage and adapted to be engaged and moved by said third member.

25 5. Apparatus according to claim 4 further characterized in that said connection between said second and third members is resilient whereby the force furnished by said second member will be resiliently applied to said grip bit.

30 6. In a drawing machine, a grip bit carriage comprising a frame, a block removably received within said frame, said block having a pair of converging channels for the guidance and slidable support of a pair of stock engaging grip bits, said channels extending through the outer face of said block adjacent their point of convergence for the reception of an extended end of the stock being drawn and for the insertion and removal of the grip bits individually, and means movable relative to and carried with the carriage and engaging said grip bits for moving said grip bits toward said face, said block and bits being removable from said carriage as a unit without disturbing said means.

35 7. In a drawing machine, a grip bit carriage comprising a support having a pair of converging channels for the guidance and slidable support of a pair of stock engaging grip bits, said channels extending through the outer face of said support adjacent their point of convergence for the reception of an extended end of the stock being drawn and for the insertion and removal of the grip bits individually, means carried with said carriage for moving said bits toward said face, removable means for moving said bits away from said face, said bits being removable from said support upon the removal of said removable

13

means without disturbing said first mentioned means.

8. In a drawing machine, a grip bit carriage comprising a support having a pair of converging channels for the guidance and slidable support of a pair of stock engaging grip bits, said channels extending through the outer face of said support adjacent their point of convergence for the reception of an extended end of the stock being drawn and for the insertion and removal of the grip bits individually, means carried with said carriage for moving said bits toward said face, means connected with said first mentioned means to move said bits away from said face, said second mentioned means being readily removable without disturbing said first mentioned means to permit the bits to be removed from said support.

9. In a drawing machine, a grip bit carriage comprising a frame, a block removably mounted in said frame and carrying a plurality of stock engaging grip bits, means within said frame to move said grip bits into engagement with said stock, said block and grip bits being removable as a unit from said frame without disturbing said means.

10. A grip bit for a drawing machine having a grip bit carriage with divergent guide surfaces thereon to slidably mount the grip bits and controlled means having plane surfaces to engage and resiliently urge the grip bits into engagement with the stock; comprising an elongated member of substantially uniform cross-section throughout the major portion of its extent and having a serrated surface for engagement with the stock to be drawn and a plane surface for engagement with said plane surface of said coating grip bit urging means.

11. A grip bit for a drawing machine having a grip bit carriage with divergent guide surfaces thereon to slidably mount the grip bits and controlled means having plane surfaces to engage and urge the grip bits into engagement with the stock and quickly detachable links interconnecting said first mentioned means and the grip bits; comprising an elongated member of substantially uniform cross-section throughout the major portion of its extent and having a surface for engagement with the stock to be drawn, a recess for the reception of a portion of one of said links, said recess extending substantially normal to the direction of movement of the grip bits.

12. In a drawing machine, a grip bit carriage comprising a frame, movable means mounted thereon, a plurality of plungers slidably mounted in said frame, said plungers having outer plane surfaces, means connecting said plungers with said movable means whereby movement of said movable means results in longitudinal movement of said plungers, a plurality of pairs of stock engaging grip bits each having a plane surface adapted to be engaged by the outer plane surface of a contiguous plunger, said plungers being so disposed that grip bits variable in number of pairs, size and disposition may be engaged and operated thereby.

13. In a drawing machine, a grip bit carriage comprising a frame having movable means mounted thereon, a plurality of plungers slidably mounted in said frame, means connecting said plungers with said movable means whereby movement of said movable means results in resilient pressure being applied to said plungers tending to move the same longitudinally, a plurality of stock engaging grip bits adapted to be engaged and individually moved by said plungers, said

14

plungers being so disposed that grip bits variable in number and disposition may be engaged and operated thereby.

14. In a drawing machine, a grip bit carriage comprising a frame having movable means mounted thereon, a plurality of plungers slidably mounted in said frame, means connecting said plungers with said movable means whereby movement of said movable means results in resilient pressure being applied to said plungers tending to move the same longitudinally, a plurality of stock engaging grip bits adapted to be engaged and individually moved in one direction by said plungers, and readily removable connecting means between said plungers and grip bits and spanning the points of engagement to individually move the grip bits in the other direction.

15. In a drawing machine, a grip bit carriage comprising a frame having a movable means mounted thereon, a plurality of plungers slidably mounted in said frame, a resilient connection between said movable means and each of said plungers whereby movement of said movable means results in independent movement of the plungers as determined by the resistance encountered by the respective plungers, and a plurality of stock engaging grip bits adapted to be engaged and individually moved by said plungers.

16. In a grip bit carriage for a drawing machine a pair of stock engaging grip bits mounted for movement toward and away from each other, a hook mounted for pivotal movement about a horizontal axis which is eccentric with respect to the center of mass of the hook, means to latch said hook in upper raised position, and linkage between said hook and said grip bits whereby upward movement of said hook moves said grip bits apart while downward movement of said hook moves said grip bits toward each other, said linkage including a unitary adjusting element which when adjusted in one direction is operative to move said grip bits toward each other and when adjusted in the opposite direction is operative to move said grip bits further apart independent of movement of said hook.

17. Apparatus according to claim 16 further characterized in that said linkage includes a link connected with said hook eccentrically of the pivot pin thereof, said unitary adjusting element constituting a portion of said link and being operative to vary the effective length of said link.

18. In a drawing machine, a grip bit carriage comprising a frame having a hook pivotally mounted thereon and movable by gravity in a generally vertical plane from upper to lower positions, and means to maintain said hook in upper raised position comprising a member supporting said hook at substantially the center of its otherwise unsupported mass, said member being carried with said frame.

19. In a drawing machine, a grip bit carriage comprising a frame having a hook pivotally mounted thereon and movable by gravity in a generally vertical plane from upper to lower positions, and means to maintain said hook in upper raised position comprising a member supporting said hook at or adjacent its center of mass or on the opposite side of said center from the pivotal axis of said hook.

20. In a drawing machine, a grip bit carriage comprising a frame having a hook pivotally mounted thereon on a transversely extending pivot pin, a plurality of plungers slidably mounted in the frame rearwardly of said pin, means connecting said plungers with said hook whereby

pivotal movement of said hook results in resilient pressure being applied to said plungers tending to move the same longitudinally, said connecting means including linkage extending underneath said pin, a plurality of stock engaging grip bits slidably mounted in said frame and adapted to be engaged and operated by said plungers, substantially the whole of said plungers, connecting means and grip bits being housed within said frame in protected positions.

21. Structure according to claim 20 further including adjusting means to vary the interval of said connecting means, said adjusting means extending outwardly a short distance beyond the general contour of said frame.

22. In a drawing machine, a grip bit carriage comprising a frame, a hook pivotally mounted thereon on a transversely extending axis, a plurality of movable stock engaging grip bits mounted in said frame rearwardly of said axis, and means depending below said axis for connecting said hook and said grip bits whereby pivotal movement of the hook will result in movement of the grip bits and the said means is in protected position within the frame.

23. A drawing machine comprising a die block, a bench extending outwardly from said block, a grip bit carriage movable along said bench toward and away from said block, means to move the carriage toward the die block, means to brake such movement as the carriage approaches the die block, means to urge said carriage toward said block as said carriage reaches a position adjacent said block, and means rendering the urging means substantially inoperative during movement of said carriage away from said block.

24. A drawing machine comprising a die block, a bench extending outwardly from said block, a grip bit carriage movable along said bench, means to move the carriage under load away from said block, independent means to move the carriage toward said block, means to brake the movement toward the block as the carriage approaches the block, means to urge said carriage into engagement with said block as said carriage reaches a position adjacent said block, means to automatically connect the first mentioned means with the carriage after the carriage reaches the block, and means operable upon initiation of movement away from the block to render said means to urge inoperative.

25. A drawing machine comprising a die, a bench extending outwardly from said die, a grip bit carriage movable along said bench, means to move said carriage toward said die comprising a cable, means to move the carriage under load away from said die, means including said cable to urge the carriage toward the die, and means responsive to the initiation of movement of said carriage away from said die to render said means to urge inoperative.

26. A drawing machine comprising in combination a die block, a bench extending outwardly from said block, a grip bit carriage movable along said bench, means to move the carriage under load away from said block, movable grip bits on said carriage, means to move said bits to material engaging positions, independent means to move said bits to open inoperative positions, means to move said carriage towards said block, automatic means to brake the movement toward the block as the carriage approaches the block, automatic means to urge said carriage into engagement with said block as said carriage reaches a position adjacent said block, means to automatically con-

nect the first mentioned means with the carriage after the carriage reaches the block, and means operable upon initiation of movement away from the block to render said means to urge inoperative.

27. A drawing machine comprising a die block, a bench extending outwardly from said block, a grip bit carriage movable along said bench toward and away from said block, means to move the carriage toward the die block, means to urge said carriage toward said block as said carriage reaches a position adjacent said block, and means rendering the urging means substantially inoperative during movement of said carriage away from said block.

28. A drawing machine comprising a die, a bench extending outwardly therefrom, a grip bit carriage movable along said bench, means to move said carriage comprising a cable secured to said carriage, a pulley at each end of said bench, a cable driving sheave having at least two grooves intermediate said pulleys, an idling sheave having at least one groove between said driving sheave and each pulley, said cable extending from the carriage thence over one pulley, one groove of the driving sheave, the idling sheave adjacent said one pulley, the other idling sheave, the other groove of the driving sheave, the other pulley and thence back to the carriage whereby the driving sheave support is substantially relieved from stress arising from static tension in the cable and the stress resulting from driving tension in the cable is applied at a constant point along the axis of said driving sheave.

29. In a drawing machine having a die, a bench extending outwardly therefrom, and a grip bit carriage movable along said bench; means to move said carriage along said bench comprising a unitary cable secured to said carriage, a cable driving sheave having at least two spaced parallel annular cable engaging tracks thereon, a sheave having at least one annular cable engaging track thereon on either side of said cable driving sheave; said cable entrained in series over one of the tracks of the driving sheave, one of the tracks of one of the second mentioned sheaves, one of the tracks of the other of said second mentioned sheaves, and one of the other of the tracks of the cable driving sheave; whereby the driving sheave support is substantially relieved from stresses due to static tension in the cable and the stress resulting from dynamic tension in the cable is applied at substantially a constant point along the axis of the driving sheave.

30. In a drawing machine having a bench and a grip bit carriage movable along said bench; means to move said carriage along said bench comprising a unitary cable secured to said carriage, a cable driving sheave having at least two spaced parallel annular cable engaging tracks thereon, an idler sheave on either side of said driving sheave; a portion of said cable being entrained over said sheaves in such manner that the position of the points of application of tension in said cable in either direction of rotation of said driving sheave does not vary longitudinally along the axis of the driving sheave.

31. In a draw head for operation in a mechanism of the class described, attaching means for positively engaging said head with a drawing member, sliding jaw members adapted to engage the work to be drawn, an operating member for each of said jaw members, linkage means actuated by said attaching means for operating said operating members, and spring means inter-con-

necting said linkage means and said operating members, said linkage means, spring means and operating members being adapted, on movement of said attaching means, to simultaneously move all of said jaw members toward the work, and said linkage and spring means being adapted to thereafter independently move any said operating member and its jaw member after any other said jaw member has positively engaged the work.

32. In a drawhead for operation in metal drawing apparatus having a workhead and means supporting said drawhead for movement away from and toward said workhead, a pair of relatively movable jaw members adapted to engage a stock piece to be drawn through said workhead, an operating member for each of said jaw members, mechanical power generating means carried on said drawhead, linkage means actu-

ated by said power means upon activation thereof for operating said operating members, lost-motion urging means interconnecting said linkage means and said operating members whereby upon activation of said power means and the subsequent arrest of movement of one of said jaw members by contact with said stock piece the other of said jaw members is continued to be urged in a direction tending to close onto said stock piece, and a control device on said drawhead for automatically effecting the activation of said power means thereby automatically effecting said closure of said pair of movable jaw members onto said stock piece upon said drawhead moving to a predetermined position adjacent said workhead.

WALLACE E. KERR.
